UNITED STATES PATENT OFFICE.

JOHN N. DERSCHUG AND GUY C. WILKINSON, OF SYRACUSE, NEW YORK, ASSIGNEES
TO SYRACUSE WASHING MACHINE CORPORATION, OF SYRACUSE, NEW YORK, A
CORPORATION OF NEW YORK.

IRONING MACHINE.

Application filed September 28, 1921. Serial No. 503,891.

To all whom it may concern:

Be it known that we, JOHN N. DERSCHUG and GUY C. WILKINSON, of Syracuse, in the county of Onondaga, in the State of New York, have invented new and useful Improvements in an Ironing Machine, of which the following, taken in connection with the accompanying drawings, is a full, clear, and exact description.

10 This invention relates to an ironing machine involving the use of a hollow heating roll or drum of suitable metal having a smooth peripheral surface, and a pair of fabric covered rolls cooperating with the 15 heating roll for laundering sheets, table-cloths, pillow-cases, spreads, napkins, hand-kerchiefs and other flat articles which are brought to the machine in a more or less dampened condition and leave the machine 20 in a smooth dry state.

In ironing articles by machines of this character, it is first necessary to straighten out the leading edge of the article by hand upon a suitable table and then to feed said 25 edge by hand between the heating roll and feeding roll in order that the machine may perform its work automatically and efficiently without any further effort upon the part of the operator other than to see that 30 the remaining portions of the article are straight or flat without wrinkles as they enter between the rollers.

In the use of machines having rigid tables across which the articles to be ironed are fed, it is necessary to bring the hands into dangerous proximity to the feeding faces of the rollers and sometimes results in serious burning of the fingers by the heating roll or in painful injury to the fingers by 35 being caught between the rolls, and one of the main objects of our present invention is to obviate these dangers by providing a supporting table for the articles to be ironed which is movable at will toward and from 40 the rollers and is automatically retracted and normally held away from said rollers a sufficient distance to allow the leading edge of the article to be properly straightened out thereon and alined with said rollers prior 45 to advancing the same to the feeding mechanism so that the advancing movement of the table automatically feeds the straightened edge to the rollers without necessitating the 50 close approach of the fingers thereto.

Another object is to provide means where-
by the feeding rollers at opposite sides of
the heating roller may automatically adjust
themselves to conform to different thick-
nesses of the articles engaged thereby.

Another object is to provide one of the
feeding rollers with an auxiliary ironing
device cooperating with a radially movable
heating element for ironing the bands of
shirts, skirts, aprons and other relatively
narrow portions of garments and other ar-
ticles.

Other objects and uses relating to specific
parts of the machine will be brought out in
the following description:

In the drawings:

Figs. 1 and 2 are, respectively, a front
elevation and a top plan of an ironing ma-
chine embodying the various features of our
invention.

Figs. 3 and 4 are enlarged transverse sec-
tional views taken, respectively, on lines
3-3 and 4-4, Fig. 2.

Fig. 5 is a transverse horizontal sectional
view enlarged taken on line 5-5, Fig. 6.

Figs. 6 and 7 are opposite end elevations
of the same machine.

Fig. 8 is a transverse vertical sectional
view taken on line 8-8, Fig. 1.

Fig. 9 is a detail sectional view taken on
line 9-9, Fig. 6.

This machine may be used in private as
well as in public laundries and comprises a
main supporting frame having upright end
standards —1— supported by suitable cast-
ers —2— to enable the machine to be easily
moved from place to place along the floor,
the standards —1— being spaced a consider-
able distance apart to adapt the machine
for ironing relatively wide articles, such as
tablecloths, spreads and the like as well as
the smaller flat articles, such as napkins,
handkerchiefs, towels and similar articles.

A hollow cylindrical roll —3— of sub-
stantially the same length as the distance
between the upright standards —1— is ro-
tatably supported at its ends upon suitable
bearings —4— to rotate about a horizontal
axis, the bearings —4— being preferably of
the roller type bearing against the underside
of the periphery of the drum —3— to per-
mit the latter to rotate with a minimum
amount of friction.

A gas burner consisting of, in this in-

- stance, a radially perforated pipe —5— is extended from one end into and through the heating drum —3— coaxial therewith for heating said drum to the desired temperature for ironing purposes, the drum being preferably made of steel or equivalent metal having a smooth peripheral surface against which the ironed articles come in direct contact in transit through the machine.
- 10 A relatively stationary baffle plate —6— is suitably supported by the upright standards —1— and extends practically the entire length of and within the heating drum —3— directly over the burner —5— leaving sufficient space as —7— at each edge of the baffle plate —6— to permit the passage of the heated products of combustion to the upper portion of the drum without liability of over heating the same.
- 15 20 The upper ends of the standards —1— are provided at their outer faces with similar pairs of upright ways —8—, those of each pair being located at equal distances from and at opposite sides of the axis of the drum —3— for receiving and guiding a vertically movable cross-heads —9— having central vertically elongated slots —10— for receiving the adjacent portions of the burner —5— and allowing vertical movement of the cross-heads without interference with said burner.
- 25 A pair of similar rock-arms —11— are centrally pivoted at —11'— to the upper end of the cross-heads —9— to rock about one and the same horizontal axis with their branches extending forwardly and rearwardly in substantially parallel planes for receiving and supporting the corresponding ends of a pair of fabric covered feeding
- 30 35 40 rollers —12— and —12'—.
- 45 These feeding rollers —12— and —12'— are journaled at their ends in suitable bearings —13— in the rock arms —11— substantially equal distances from and at opposite sides of the vertical plane of the axes of the pivots —11'— and heating drum —3— to cooperate with the upper surface of the heating drum in feeding the articles to be ironed through the machine and simultaneously smoothing and ironing the same.
- 50 55 60 The rollers —12— and —12'— are rotated in the same direction indicated by the arrow in Fig. 3 and for this purpose, are provided at one end with gears —14— meshing with an intermediate drive gear —15—, which in turn is journaled upon the central portion of the rock-arm —11— so that the gears will always remain in mesh in any position of rocking movement of the arms —11— or vertical movement of the cross-heads —9—.
- 65 The driving gear —15— is preferably secured to the inner ends of a stud shaft —16—, which in turn is journaled in the rock arm —11— and is provided with a pair
- 70 75 80 85 90 95 100 105 110 115 120 125 130 of sprocket wheels —17— and —18— of unequal size connected, respectively, by chains —17'— and —18'— to driving sprocket wheels —19— and —20— also of different size within a suitable gear housing —21— on the adjacent upper portion of the standard —1—, the larger sprocket wheel —17— being connected by chain —17'— to the smaller sprocket wheel as —19—, while the smaller sprocket wheel as —18— on the shaft —16— is connected to the larger sprocket wheel within said gear housing, the object of these sprocket wheels of different sizes being to provide different speeds by which the feeding rollers may be operated.
- 90 95 100 105 110 115 120 125 130 The sprocket wheels —19— and —20— are preferably loosely mounted upon a supporting shaft —22— carrying an intermediate clutch collar —23— splined thereon and normally in a neutral position between the sprocket wheels —19— and —20— but adapted to be forced into engagement with either by an operating handle —24— connected thereto.
- 100 105 110 115 120 125 130 The shaft —23— is provided with a worm wheel —25— tight thereon and meshing with a worm —26— on a shaft —27— which is journaled in the gear housing —21— and is provided with an external pulley —28— connected by a belt —29— to electric motor —30—, the latter being also mounted upon the main supporting frame to form a unitary part of the machine as the source of power for rotating the rollers.
- 105 110 115 120 125 130 The cross-heads —9— carrying the rock-arms —11— and feeding rollers —12— and —12'— are movable vertically along the guideways —8— by means of a pedal lever —31— extending rearwardly from the front of the machine near the base thereof and having its rear end fulcrumed at —32— upon said frame and its front end provided with a pedal —33— by which the lever —31— may be depressed by the operator against the action of a retracting spring —34—, the intermediate portion of said lever being connected by a link —35— to a crank-arm —36—, which is secured to a longitudinally extending shaft —37— having its ends journaled in suitable bearings —38— in the upright standards —1— and provided with additional crank-arms —39—.
- 110 115 120 125 130 These crank-arms —38— are provided with longitudinally extending lugs —39— having apertures therethrough for receiving the adjacent ends of a pair of links —40— having their upper ends pivotally connected at —41— to the lower ends of the cross-heads —9—. The lower ends of the links —40— extend through and some distance beyond the lugs —39— and are preferably threaded for receiving nuts —42— and —43—, the nuts —42— constituting shoulders or abutments for the lower ends of a pair of coil springs —44— which encircle

the adjacent portions of the links and have their upper ends abutting against the underside of the lugs —39— to form yielding connections between the links and crank-arms —38—, and thereby to allow the rollers —12— and —12'— to be brought into pressing coaction with the heating drum —3— with a yielding pressure and also enables the rollers to adjust themselves to varying 10 thicknesses of the articles which may be fed through the machine, while the tilting action of the arms —11— about their pivots —11'— enables the rollers —12— and —12'— to automatically adjust themselves 15 to different thicknesses of the same articles or of different articles.

Suitable means is provided for locking the pedal lever —31— and parts operated thereby in their pressing position, said 20 means consisting of, in this instance, a latch —46— pivoted at —47— to the lever —31— and provided with a pendant hook —48— movable into and out of engagement with a rod —49— on the main supporting frame 25 so that when the pedal lever is depressed, the latch —48— will automatically interlock with a catch —49— to hold the lever in its extreme downward position and thereby to hold the rollers —12— and 30 —12'— in their pressing coaction with the drum —3—.

The latch —46— is provided with a forward extension —50— having a lug —51— projecting through an opening in the pedal 35 —33— to be engaged by the foot of the operator when desired to trip the catch —46—, and thereby to release said lever —31— and parts operated thereby, thus enabling the spring —34— to retract the lever 40 and to raise the rollers —12— and —12'— out of pressing coaction with drum —3— ready for the reception of the articles to be ironed.

The upper ends of the standards —1— 45 are provided with forwardly projecting horizontal guides —52— for supporting a forwardly and rearwardly movable table —53— upon which the articles to be ironed may be supported preparatory to feeding 50 the same into the machine or between the feeding rollers and heating roller.

The horizontal reciprocatory movement 55 of the table —53— is preferably synchronized with the vertical reciprocatory movement of the cross-heads —9— and press rollers —12— and —12'— carried thereby so that the table after the work has been properly straightened and smoothed thereon may feed the work to the rollers simultaneously with the depression of the pressure 60 rollers and for this purpose, a pair of upright links or levers —54— are pivotally connected at their upper ends to the table —53— and have their lower ends pivotally 65 connected to the frame standards —1— at

—55— near the base of said frame, the intermediate portions of said links or levers —54— being connected by relatively short links —56— to a pair of crank arms —57— on the rock-shaft —37— just at the inner 70 sides of the standards —1—, whereby when the rock-shaft —37— is operated by the lever —31— to force the pressing rollers —12— and —12'— into pressing coaction with the heating drum —3—, the table 75 —53— with the work thereon will be advanced toward said drum to bring the leading edge of the work into engagement with the feeding roller —12—, which by reason of its overhanging position relatively to the rear edge of the table —53— comes in direct frictional contact with the upper surface of the work when the rollers are depressed to assure the feeding of the leading 80 edge of the articles between the rollers. 85

That is, the front roller —12— is disposed in a vertical plane some distance in front of the front face of the heating drum —3— while the table —53— is disposed in a horizontal plane partly below that of the upper 90 face of the heating drum and directly below the lower face of the feeding roller —12— so that its upper surface carrying the work would be engaged by the periphery of the roller —12— when both of the feeding rollers are depressed to assure the frictional engagement and feeding of the work between the rolls for ironing purposes. 95

A guide-plate —58— is secured in the frame of the machine between the upright 100 standards —1— to extend the entire length of the heating drum and also forwardly and downwardly from the rear face thereof in spaced relation thereto to receive the leading edges of the ironed articles and to 105 direct them forwardly within easy reaching distance of the operator at the front of the machine.

A stripper-plate —59— is also mounted within the machine and between the upright 110 standards —1— to extend practically the entire length of the heating drum —3— at the lower front side thereof and is provided with a series of stripper fingers preferably of spring metal spring pressed against the 115 periphery of the drum for stripping any articles therefrom which may tend to adhere thereto and causing the articles to fall upon the underlying guides —58—.

One of the feeding rolls as the rear roll 120 —12'— is extended through and some distance beyond one end of the frame of the machine and is provided with a supplemental ironing roll —60— coaxial therewith but external to the frame of the machine 125 to cooperate with a vertically movable press-head —61— at the upper side thereof for ironing relatively narrow articles, such as the bands or marginal edges of otherwise flat work, said press-head —61— being 130

4
mounted on the outer end of a rock-arm —62— which is fulcrumed at —63— to the upper portion of the adjacent side or end of the machine to swing vertically lengthwise thereof or about an axis at right angles to that of the roller —12'— and heating drum —60—.

The pivot —63— preferably consists of a rock-shaft having a crank arm —64— connected by a link —65— to a supplemental pedal lever —66— which is pivoted or fulcrumed at —67— to the base of the adjacent end of the machine to rock vertically against the action of the retracting spring —68— which yieldingly holds the press-head —61— and its operating means in an elevated position, as shown in Fig. 1.

The ironing drum —60— is preferably made of metal having a smooth cylindrical periphery, while the press-head —61— is also made of metal and is provided with a heating chamber for receiving a gas burner which, in this instance, consists of the inner end of the rock-arm —62—, the latter being tubular and connected by a flexible hose or pipe —69— to a suitable source of gas supply not shown, the lower face of said press-head —61— being concaved in cross-section to conform to the periphery of the roller —60—.

If desired, the supplemental drum —60— may be covered with fabric to assist in frictionally feeding the articles against the concaved heated face of the press-head —61— when the latter is in pressing position.

The operation briefly stated is as follows: Assuming that the various parts of the machine are in their normal position with the table —53— withdrawn from the rollers —12— and —3— and that the rollers —12— and —12'— are elevated away from the heating drum. Then, the operator first straightens the leading end of the article to be ironed upon the upper face of the table —53— with said leading edge alined with the rear edge of the table but a sufficient distance away from the rollers to prevent contact of the fingers therewith whereupon the pedal lever —21— may be depressed to move the table —53— with the work thereon rearwardly toward the pressing rollers and to simultaneously bring the pressing rolls into pressing coaction with the heating drum —3—, thereby causing the lower face of the roller —12— to engage the upper surface of the article on the table —53— and to feed the same between the rollers for ironing purposes, the lever —31— being then locked in its down position by the catch —46— to hold the table —53— and pressing rollers in operative position while the work is fed through the machine, the completed work being returned along the upper face of the guide —58— to the operator beneath the table —53—.

As soon as the ironing operation is completed, the catch lever —46— may be released by light pressure of the foot upon the part —51—, thus permitting the work table and pressure rollers to return to their normal positions.

In ironing relatively narrow articles, they are simply placed upon the upper face of the roller —60— and pressed thereagainst by the depression of the press-head —61— through the medium of the pedal lever —66—, said press-head and its supporting arm —62— being adjustable lengthwise in a supporting-head —70— and is held in its adjusted position by a set screw —71—, the object of this adjustment being to enable the operator to use the outer end of the pressing surface of the press-head at any part along the length of the roller —60— particularly when pressing the band or marginal edges of certain articles.

The stripping plate —59— is preferably mounted upon the rock-shaft —59'— which is journaled in the upright standards —1— and is provided with pendant arms —72— engaged by adjusting screws —73— on said frame for tightening the stripping fingers against the periphery of the drum —3— when desired.

What we claim is:

1. In an ironing machine of the character described, the combination with the work feeding rollers and an ironing drum, of a work supporting table movable toward and from the feeding and ironing means and means for synchronously moving the rollers and work table toward and from the drum.

2. In an ironing machine of the character described, the combination of a heating drum, a feeding roller movable toward and from the drum, a work-supporting table movable in a plane tangential to the feeding roller, and means for synchronously moving said table and roller toward and from the heating drum.

3. In an ironing machine of the character described, the combination of a frame, a rotary heating drum, a pair of pressure rollers extending lengthwise of the drum, cross-heads slidable on the frame, supports for the pressure rollers pivoted to the cross-heads to rock laterally, and means for reciprocating said cross-heads.

4. In an ironing machine of the character described, the combination of a rotary heating drum, a pair of pressing rollers extending lengthwise of the drum, a supporting frame for the drum, cross-heads slidable on the frame radially of the drum, supports for the pressing rollers pivotally mounted on the cross-heads to rock about an axis parallel with that of the drum, and means for reciprocating said cross-heads.

5. In an ironing machine of the character described, the combination of a frame, a

- heating drum, pressure rollers extending lengthwise of said drum, supporting means for said pressure rollers, a work-table slidable horizontally on the frame toward and from the heating drum, means operable at will for reciprocating the supporting means vertically, and additional means actuated by the last named means for reciprocating the work-table.
- 10 6. In an ironing machine of the character described, the combination of a supporting frame, a heating drum journaled on the frame, a work-table slidable upon the frame toward and from the drum, a crank-shaft mounted on the frame, levers pivotally connected to the frame and to said work-table, means including a pedal lever for operating said crank-shaft, and links connecting the crank-shaft with said levers for reciprocating said work-table as the crank-shaft is operated by the pedal lever.
7. In an ironing machine of the character described, the combination of a frame, a heating drum mounted on the frame, cross-heads slidable radially of the drum upon said frame, rock-arms mounted on the cross-heads, pressure rolls mounted on the rock-arms, a crank-shaft journaled on the frame, connections between the crank-shaft and cross-heads for reciprocating the same as the crank-shaft is rocked, means for rocking the crank-shaft, a work-table slidably mounted

upon the frame toward and from the drum, levers pivotally connected to the frame and to the work-supporting-table, and connections between the crank-shaft and said levers for reciprocating the work-table simultaneously with the operation of the cross-heads.

8. In an ironing machine of the character described, a main frame, a heating drum rotatably mounted on the frame, cross-heads slidable vertically on opposite ends of the frame, rocker arms pivoted to the cross heads, pressure rollers journaled on the rocker arms at opposite sides of their pivots, and means for reciprocating said cross heads.

9. In an ironing machine of the character described, a main frame, a heating drum rotatably mounted on the frame, cross heads slidable vertically on opposite ends of the frame, rocker arms pivoted to the cross heads, pressure rollers journaled on the rocker arms at opposite sides of their pivots, a work table slidable horizontally on the frame toward and from the drum and means for synchronously reciprocating the cross heads and work table.

In witness whereof we have hereunto set our hands this 22nd day of September, 1921.
